UNITED STATES PATENT OFFICE

114,750

DESIGN FOR A HOLDER FOR PAPER NAPKINS OR THE LIKE

Robert F. Carpenter, Cleveland, Ohio

Application March 21, 1938, Serial No. 75,990

Term of patent 7 years

To all whom it may concern:

Be it known that I, Robert F. Carpenter, a citizen of the United States, residing at Cleveland, in the county of Cuyahoga and State of Ohio, have invented a new, original, and ornamental Design for a Holder for Paper Napkins or the like, of which the following is a specification, reference being had to the accompanying drawing, forming part thereof.

Fig. 1 is a side elevation of a holder for paper napkins or the like, showing my new design;
Fig. 2 is an end elevation thereof; and
Fig. 3 is a view taken on line 3—3 of Fig. 1.

I claim:

The ornamental design for a holder for paper napkins or the like, as shown.

ROBERT F. CARPENTER.
